UNITED STATES PATENT OFFICE.

LEONARD F. BELLINGRATH, OF ATLANTA, GEORGIA.

VALVE OPERATING AND INDICATING MECHANISM.

1,003,131.

Specification of Letters Patent. Patented Sept. 12, 1911.

Application filed August 17, 1910. Serial No. 577,608.

To all whom it may concern:

Be it known that I, LEONARD F. BELLINGRATH, a citizen of the United States, residing at Atlanta, in the county of Fulton and State of Georgia, have invented certain new and useful Improvements in Valve Operating and Indicating Mechanism; and I do hereby declare the following to be a full, clear, and exact description of the invention, such as will enable others skilled in the art to which it appertains to make and use the same.

This invention relates to improvements in valve indicating posts, and has for an object to provide improved means for operating a valve to indicate from the position of the operating means whether the valve is open or closed.

A further object of the invention is to provide a cap for a service box or indicator post hereinafter referred to simply as a service box with means carried by the cap for engaging and rotating the valve stem when the cap is rotated, and with a lever carried by the cap which is held upwardly in position when the valve is closed, and with means for locking it down when the valve is open, and with an extension showing the word "Open" appearing on both sides and a plate having the word "Closed" appearing on both sides, these words being exhibited in turn as the valve is open or closed.

With these and other objects in view the invention comprises certain novel constructions, combinations and arrangement of parts as will be hereinafter more fully described and claimed.

In the drawings: Figure 1 is a view in vertical diametrical section of the service box with the improved operating means attached thereto with the lever shown in open position and locked with the extension of lever in a vertical position and the word "Open" exhibited on the side. Fig. 2 is a view similar to Fig. 1 except that the lever is shown in extended or closed position, and locked in such position with the plate attached to the lever in a horizontal position and the word "Closed" exhibited on the side. Fig. 3 is a top plan view of the

improved structure. Fig. 4 is a top plan view of the service box with cap removed.

Like characters of reference designate corresponding parts throughout the several views.

Forming a part of the present invention is a service box 10 of substantially the usual and ordinary construction, with a valve stem 11 extending longitudinally therethrough to the usual and ordinary valve not shown. The upper end of the service box is provided with an annular rack or circumferential gear teeth 12, and also with one or more peripheral ribs 13 spaced below the rack 12. Upon the upper end of the service box is a cap 14 having an annular groove or furrow to receive the upper end of the service box, and also with a groove or furrow to receive the rib 13. The part of the cap 14 which extends into the upper end of the service box is provided with a central polygonal opening to receive the polygonal extremity 15 of the stem 11.

Outstanding at one side of the cap 14 are ears 16 to which is pivoted as at 17 a lever or handle 18, by which the cap 14 may rotate upon the upper end of the service box when the lever is extended in the position shown at Figs. 2 and 3. The lever 18 is provided with a socket 19 substantially longitudinal thereof and proportioned to receive a sleeve 20 which is mounted to slide diametrically of the cap 14. When the sleeve 20 is extended, as shown in Fig. 2, it is inserted part way into the socket 19 of the lever 18, and spans the hinge line of such lever and holds such lever in extended or closed position as shown in Figs. 2 and 3. To produce longitudinal movement of the sleeve 20, a screw 21 is journaled within the cap 14, and is actuated by means of a pinion 22 meshing with the annular rack 12 formed upon the upper end of the service box. The service box is also provided with outstanding ears 23 between which the lever 18 is received when in open position as shown in Fig. 1, and may be secured therein in any approved manner as by the use of the lock 24. The ears 23 are also provided with wings 25, and the lever 18 with a plate 26 upon which will preferably

appear the word "Closed" and an extension 26 upon which will preferably appear the word "Open" as shown, so that when the lever is extended and locked in closed position as shown at Fig. 2, the word "Closed" will be properly exhibited and the word "Open" hidden by the ribs 26' upstanding on the cap 14 to indicate the condition of the valve, but when turned 10 downwardly to open position as shown at Fig. 1, the word "Closed" and the plate 26 carrying such word will be hidden and the word "Open" exhibited on the extension 26' as shown in Fig. 1. Preferably 15 there is also pivoted upon the cap 14 a detent 27 positioned to engage a shoulder 28 carried by the lever to temporarily hold such lever in extended position while the valve is being operated in either direction. 20 It will be apparent that when the valve is in open position as shown at Fig. 1 the structure is locked by the use of the lock 24 against unauthorized actuation and the extension 26' of the lever with the word 25 "Open" exhibited indicating the position of the attached valve. When it is desired to close the valve the lock 24 is of course removed, the lever 18 extended, and the cap rotated until the valve is closed, which also 30 rotates the pinion 22 and extends the sleeve 20 to hold the lever in extended or closed position and the plate with the word "Closed" is exhibited indicating the position of the attached valve. 35 While the positions shown at Figs. 1 and 2 have been designated respectively as "open" and "closed" positions, it is apparent that the device could be modified so 40 that such positions may indicate the reverse position of the valve, to wit: a valve which is to remain normally closed would be indicated as closed by the position of the lever, as shown at Fig. 1, while when it is open the lever would be extended as at Fig. 2, and 45 of course the words "Closed" and "Open" appearing upon the respective posts would be transposed.

What I claim is:—

1. The combination with a service box 50 and valve stem therein, of a wrench for turning the stem rotatably secured upon the upper end of the service box, a radially extending lever pivotally secured to the wrench, and means carried by the wrench 55 for automatically locking the lever in extended position when the stem has been rotated.

2. The combination with a service box and valve stem therein, of a wrench rotatably secured upon the upper end of the service box, 60 a lever pivotally carried by the wrench, means carried by the wrench adapted to slidably engage and lock the lever in extended position, and means carried by the

wrench and engaging the service box for 65 actuating the locking means.

3. The combination with a service box and valve stem therein, of a wrench rotatably carried upon the upper end of the service box and engaging the stem, a lever 70 pivotally carried by the wrench and adapted to extend radially, a reciprocatable member carried by the wrench and adapted to engage and lock the lever in extended position, and a rotatable member carried by the 75 wrench adapted to actuate the reciprocatable member.

4. The combination with a service box having a valve stem therein, of a wrench member for turning the stem rotatably secured upon the upper end of the service box, a lever pivotally carried by the wrench, means carried by the service box for locking the lever in retracted position, means carried by the wrench for automatically locking 80 the lever in extended position, and means engaging the service box for actuating the last named locking means.

5. The combination with the service box having gear teeth formed at its upper edge, 90 of a cap rotatably mounted upon the service box, a lever pivotally carried by the cap, a sleeve radially slidable within the cap and adapted to automatically engage and lock the lever in extended position when the cap 95 is rotated in one direction, and a pinion engaging the gear teeth of the service box operatively connected to the cap and adapted when rotated to move the sleeve.

6. The combination with a service box 100 having gear teeth formed at its upper edge, of a cap rotatably mounted upon the upper edge and provided with a groove adapted to receive the gear teeth, a lever pivotally carried by the cap, a sleeve radially movable 105 relative to the cap and adapted to automatically engage and lock the lever in extended position when the cap is rotated in one direction, a screw diametrically positioned relative to the cap and adapted when rotated 110 to move the sleeve, a pinion carried by the screw in engagement with the gear teeth of the service box and operatively connected with the cap and adapted to actuate the screw, an extension to the lever with a position designation thereon, and a plate attached to the lever with a position designation thereon, such extension and plate being singly and alternately exhibited and hidden according to the position of the 120 valve and operating device.

7. The combination with a service box having a valve stem operatively connected with the cap of the box disposed therein, of a rib formed about the upper edge of the 125 service box, a cap disposed upon the upper end of the service box and provided with an annular groove engaging upon the rib, a

lever having a socket pivoted upon the cap and adapted to extend radially therefrom a sleeve movable within the cap, a screw engaging the sleeve and adapted to advance 5 the sleeve into the socket in the lever and thereby lock the lever when in its radially extended position and means carried by the screw engaging the upper end of the serv- ice box adapted to rotate the screw when the cap is rotated. 10 In testimony whereof I affix my signature in presence of two witnesses.
